ALEXIS JACCARD, OF ST.-CROIX, SWITZERLAND, AND JULIEN KOFF, OF LONDON, ENGLAND.

FAN WITH FOLDING BLADES.

1,356,286.

Specification of Letters Patent.

Patented Oct. 19, 1920.

Application filed March 26, 1920. Serial No. 368,996.

To all whom it may concern:

Be it known that we, ALEXIS JACCARD, a citizen of the Swiss Confederation, and residing at St.-Croix, Canton of Vaud, Switzerland, and JULIEN KOFF, a citizen of the Russian nationality, and residing at No. 5, Victoria Arcade, Victoria street, London, S. W. 1, England, have invented certain new and useful Improvements in and Relating to Fans with Folding Blades, of which the following is a specification.

This invention consists in improvements in rotary fans of the folding blade type.

The improvements relate more particularly to the manner of actuating the fan blades.

The fan blades are mounted in the usual manner by means of a hub with a friction fit on the shaft of a pinion, and according to the present invention the blades unfold automatically when the fan is started.

The fan blades are driven by a toothed wheel actuated by means of a push which is adapted to rock around the shaft on which the fan blades are mounted, and to drive a crank fixed to a ratchet wheel.

A constructional form of an improved fan of the folding blade type is illustrated by way of example in the accompanying drawings, in which:—

Figure 1 is a rear view of the improved fan after removal of the cover; the push being in its position of rest.

Fig. 2 is a similar view of the improved fan, but with the push in the position into which it has been moved for the purpose of actuating the fan blades.

Fig. 3 is a front view of the improved fan closed with its cover; one of the fan blades being shown unfolded, and the others broken off in part.

Fig. 4 is a side view of the fan blades when folded.

As shown, *a* is a back frame plate carrying all the necessary toothed wheels for rotating the fan blades *b*. The fan blades are mounted on a metal hub composed of two plates, the upper one *b*¹ of which has three abutments parallel to the axis of the bore of the hub. These abutments are situated 120 degrees apart from one another around this axis, and their lengths differ from one another by the thickness of a fan blade.

The entire combination of fan blades and hub is mounted with a friction fit on a

conical shaft *c* carrying a pinion that meshes with the movable members of a train of toothed wheels terminating in a wheel *d*. This latter wheel carries a pawl which is engaged, by the action of a spring, in a ratchet wheel *e* coaxial to the wheel *d* and fixed to a crank *f* whose pin is engaged in the slide-way of a push *g* adapted to rock around the shaft *c*.

The several toothed wheels are held in place by a bridge *h* fixed by screws in the rear frame plate *a*. The whole is covered in by a cover *i* provided with a finger piece *i*¹ against which the operator places his fingers and which takes the reaction of the effort exerted by the operator upon the push *g* in starting the apparatus.

This starting is effected by the operator's moving the push *g* toward the finger piece *i*¹ by means of his thumb and fore-finger. The rocking movement of the push *g* acts upon the crank in a counterclockwise direction, and this motion is transmitted through the medium of the ratchet carried by the wheel *d*, to the train of toothed wheels, and thence to the pinion *c* on the shaft of which latter the fan blades are mounted.

The fan blades begin their rotation, and if they are in their folded condition, they will unfold automatically by reason of the fact that the air has a tendency to prevent them from rotating. The fan blades thus slide over one another; the first blade remains fixed because it is held by an abutment *b*² of exactly the width of a blade, and a stop *b*³ that connects the two plates constituting the hub.

The second blade moves back until it reaches the second abutment *b*²⁰ which has a length equal to the width of two fan blades; and the third blade moves back until it abuts against the third abutment *b*²¹.

The push *g* is returned into its initial position by the action of a spring *r* upon the pin of the crank. This movement, however, does not affect the fan blades. These have acquired a certain amount of kinetic energy which keeps them moving, while the ratchet of the wheel *d* merely slips over the wheel *e* when the latter is revolving in the opposite direction to that of the wheel *d*.

The push resumes the position shown in Fig. 1, and the operation of the parts may be repeated in order to keep the fan blades revolving.

Having now described our invention what we claim as new and desire to secure by Letters Patent is:—

A rotary fan of the folding blade type, comprising in combination a shaft, a hub member on said shaft, comprising a plate provided with abutments which are parallel to the axis of rotation, situated 120 degrees apart from one another, and whose respective 10 lengths differ progressively from one another by the thickness of a fan blade, a plurality of blades frictionally held in said hub, and adapted automatically to unfold upon rotation of said shaft, a push member rocking 15 about the shaft, a crank pivotally mounted on said push member, a ratchet wheel carried by said crank, a train of toothed gear-

ing, a pawl carried by one element of said train and engaging said ratchet wheel whereby movement of the push member in 20 one direction causes rotation of the shaft through said gearing, and resilient means for returning the push member to normal position after the latter has been moved to cause said rotation of the shaft. 25

In testimony whereof we have signed our names to this specification.

ALEXIS JACCARD.
JULIEN KOFF.
